FIGURE 1 is a perspective view of a first embodiment of the invention taken from below showing our new design as it appears in use. The heavy line shading represents unilluminated surfaces of opaque material. The medium line shading represents illuminated surfaces of light colored opaque material. The light line shading represents surfaces of translucent material;

FIGURE 2 is a cross sectional view of the first embodiment of the invention taken on the line 2-2 of FIGURE 1;

FIGURE 3 is a bottom view of the first embodiment of the invention;

FIGURE 4 is a perspective view of a second embodiment of the invention taken from below showing our new design as it appears in use. The heavy line shading represents unilluminated surfaces of opaque material. The medium line shading represents illuminated surfaces of light colored opaque material. The light line shading represents surfaces of translucent material;

FIGURE 5 is a cross sectional view of the second embodiment of the invention taken on the line 5-5 of FIGURE 4;

FIGURE 6 is a bottom view of the second embodiment of the invention;

FIGURE 7 is a perspective view of a third embodiment of the invention taken from below showing our new design as it appears in use. The heavy line shading

represents unilluminated surfaces of opaque material. The medium line shading represents illuminated surfaces of light colored opaque material. The light line shading represents surfaces of translucent material;

FIGURE 8 is a cross sectional view of the third embodiment of the invention taken on the line 8-8 of FIGURE 7;

FIGURE 9 is a bottom view of the third embodiment of the invention.

The dotted lines shown in FIGURES 2, 5 and 8 are disclosed for illustrative purposes only.

This is a continuation of design applications Ser. No. D.404, D.409 and D.410, each filed Jan. 3, 1966 and now abandoned.

We claim:

The ornamental design for a light diffusing grille, substantially as shown and described.
